APPARATUS FOR CONTROLLING HIGHWAY
CROSSING SIGNALS

William H. Claus, Downers Grove, Ill., assignor to
The Union Switch & Signal Company, Swiss-
vale, Pa., a corporation of Pennsylvania

Original application March 3, 1936, Serial No.
66,835. Divided and this application June 3,
1937, Serial No. 146,237

6 Claims. (Cl. 246—130)

My invention relates to apparatus for controlling highway crossing signals.

The present application is a division of my pending application, Serial No. 66,835, filed on March 3, 1936, for Interlocking relays.

I shall describe one form of apparatus embodying my invention, and shall then point out the novel features thereof in claims.

In the accompanying drawings, Fig. 1 is a diagrammatic view showing one form of apparatus embodying my invention. Fig. 2 is a view, partly diagrammatic and partly in isometric projection, showing the mechanical construction of the relay R¹ shown in Fig. 1.

Similar reference characters refer to similar parts in both views.

Referring first to Fig. 1, the reference characters 32 and 33 designate the track rails of a stretch S of railway track over which traffic normally moves in both directions. The rails 32 and 33 are divided, by means of insulated joints 34, to form three adjacent track sections D—E, E—F, and F—G, the middle section E—F being relatively short and being intersected by a highway H.

Associated with the track sections D—E, E—F, and F—G is a track relay R¹ which, as best seen in Fig. 2, comprises three electromagnets A, B, and C mounted end for end on a top plate 1 of suitable insulating material, such for example, as a phenol condensation product. The electromagnets A, B, and C are similar, and the corresponding parts of each are designated by the same reference characters with the distinguishing exponents a, b, and c added thereto. It is believed, therefore, that a description of one electromagnet will suffice for all. Referring particularly to the electromagnet A, this electromagnet comprises two parallel cores 2^a connected together at their upper ends by a back-strap 3^a, and provided at their lower ends with enlarged pole pieces 4^a located on the underside of the top plate 1. The cores 2^a each carry a winding or coil 5^a, which windings are intended to be connected in series in the usual and well-known manner.

A non-magnetizable bracket 6^a is attached to the rear sides of the pole pieces 4^a, and pivotally supported on trunnion screws 7^a mounted in depending lugs 8^a provided on the ends of the bracket 6^a is a tractive armature 9^a which carries a plurality of contact fingers 10^a, 11^a, 12^a, and 13^a. When the electromagnet A is energized, the armature 9^a is drawn upwardly to the position in which it is shown in the drawings, and under

these conditions the contact fingers 10^a, 11^a, 12^a, and 13^a each engage an associated fixed contact member 14^a to close front contacts 10^a—14^a, 11^a—14^a, 12^a—14^a, and 13^a—14^a. When, however, the electromagnet A is deenergized, the armature 9^a drops downwardly under the influence of gravity, and except under certain conditions which will be described hereinafter, the contact fingers 10^a, 11^a, 12^a, and 13^a then each engage an associated fixed contact member 15^a to close back contacts 10^a—15^a, 11^a—15^a, 12^a—15^a, and 13^a—15^a. The contact fingers 10^a, 11^a, 12^a, and 13^a are secured to the armature 9^a by means of insulating supports 16^a, and it will be apparent, therefore, that these contact fingers are insulated from the armature and from each other.

The electromagnets B and C control armatures 9^b and 9^c, respectively, which armatures are pivotally supported in a manner similar to the armature 9^a, and each of which carries contact fingers which cooperate with fixed front and back contact members to close front and back contacts in the same manner that the contact fingers 10^a, 11^a, 12^a, and 13^a carried by the armature 9^a cooperate with fixed front contact members 14^a and back contact members 15^a to close front and back contacts.

The armatures 9^a and 9^b are interlocked by interlocking mechanism comprising two arms 30¹ and 31¹ which are attached, respectively, to these armatures, and which cooperate with a locking dog 17¹ pivotally mounted on a shaft 18¹. The dog 17¹ is provided with a horizontal arm 19¹ and a vertical arm 20¹, and is biased to rotate, in a counterclockwise direction, to an inoperative position in which the vertical arm 20¹ engages a stop arm 38¹, by a counterweight 21¹ which is secured to the outer end of the horizontal arm 19¹. The inner end of the arm 19¹ is provided with an upstanding projection 22¹ which cooperates with a resilient strip 23¹ attached to the interlocking arm 31¹. When the armature 9^b is released and drops, the flexible strip 23¹ engages the projection 22¹ of the horizontal arm 19¹ of the dog 17¹ shortly after the armature passes its mid-stroke position, and during the remainder of the downward stroke of the armature, the dog 17¹ is rotated in a clockwise direction, in opposition to the bias exerted by the counterweight 21¹, to an operative position in which the upper end of the vertical arm 20¹ is in the path of downward movement of an offset portion 24¹ forming a part of the arm 30¹. If armature 9^a is then released, the downward movement of this armature will be limited by engagement of the offset portion 24¹ with the upper

end of the vertical arm 20¹. The parts are so proportioned that when the offset portion 24¹ engages the vertical arm 20¹ in this manner, the armature 9^a will be held at approximately its 5 mid-stroke position, and both the front and back contacts controlled by the armature 9^a will then be open. Furthermore, when the offset portion 24¹ engages the vertical arm 20¹ in this manner, a tip 25¹ formed on the end of a retaining spring 10 26¹ attached to the arm 30¹ extends downwardly past the outer edge of the upper end of the vertical arm 20¹, thus holding the dog in place underneath the offset portion 24¹, and thereby 15 insuring that armature 9^a cannot move to the position in which it back contacts are closed. When electromagnets A and B again both become energized, so that the armatures 9^a and 9^b are both moved to their upper positions, the counter-weight 21¹ returns the dog 17¹ to its inoperative 20 position against the stop rod 38¹, in which position the vertical arm 20¹ is out of the path of movement of the offset portion 24¹. If armature 9^a is released and drops before armature 9^b, the offset portion 24¹ will move downwardly past 25 the upper end of the arm 20¹ of the dog 17¹, but the tip 25¹ of the retaining spring 26¹ will engage the upper end of the arm 20¹. The retaining spring 26¹, however, is very flexible, and it will be apparent, therefore, that it will offer very 30 little resistance to the downward movement of the armature 9^a, so that the armature will close its back contacts under these conditions with substantially the same contact pressure as would be the case if the interlocking arm 30¹ were not attached to the armature.

The armatures 9^c and 9^b are interlocked by interlocking mechanism which is similar in all respects to, and which operates in the same manner as, that just described for interlocking the armatures 9^a and 9^b. The various parts of the mechanism for interlocking the armatures 9^c and 9^b are designated by the same reference characters as the corresponding parts of the mechanisms for interlocking the armatures 9^a and 9^b, but with the exponent 2 added, and it is believed, therefore, that a detailed description of the mechanism for interlocking the armatures 9^c and 9^b is unnecessary.

It should be pointed out that the dogs 17¹ and 50 17² are very light in weight and are loosely pivoted on the associated shafts 18¹ and 18², so that the force required to drive these dogs is small. The flexible strips 23¹ and 23² need only be stiff enough to drive the dogs 17¹ and 17² without causing deflection of the strips, and it will be apparent, therefore, that these strips may be constructed to bend under sufficiently small pressures so that they will not prevent the armature 9^b from closing its back contacts even though one of the dogs 17¹ 55 or 17² is prevented from rotating to its full operative position due to the armature 9^b or the armature 9^c having previously been released. If desired, back-stops 28¹ and 28² of rigid material may be provided to determine accurately the position 60 at which the strips 23¹ and 23² will engage the associated dogs 17¹ and 17² during the downward stroke of the armature 9^b. Furthermore, top-stops 29¹ and 29² may also be provided with clearance above the strips, so that if some unusual 65 resistance to the movement of the dogs should develop that would cause abnormal deflection of the strips 23¹ and 23², the associated topstop 29¹ or 29² would engage the strips and would limit the amount of deflection of the strips so that the 70 corresponding locking dog would still be driven 75

into the path of movement of the associated offset portion 24¹ or 24² and past the tips 25¹ and 25² of the retaining springs 26¹ and 26².

It will be seen that with a relay constructed in the manner described, if either electromagnet A or electromagnet C becomes deenergized before electromagnet B, the armature 9^a or the armature 9^c, as the case may be, will drop to its lowermost position in which the associated back contacts are closed, but that, if either electromagnet A or electromagnet C becomes deenergized subsequently to electromagnet B, the armature 9^a or the armature 9^c, as the case may be, will be prevented from dropping past the position in which the associated front and back contacts are all open.

Referring now again to Fig. 1, section D—E is provided with a track circuit comprising a battery 35, connected across the rails adjacent the end of the section which is farthest away from the highway H, and the magnet C of interlocking relay R¹ connected across the rails, at the end nearest the highway H, in series with front contact 10^b—14^b of relay R¹. Section F—G is provided with a similar circuit which includes a battery 36, the rails 2 of the section, magnet A of relay R¹, and front contact 11^b—14^b of relay R¹. Section E—F is provided with a track circuit which includes a battery 37 connected across the rails at one end of the section, and the magnet B of relay R¹ connected 3 across the rails at the other end of the section.

A signal L which, as here shown, is an electric bell, is located adjacent the intersection of the highway H and the stretch S, and this signal is provided with a circuit which includes a battery J 3 and back contacts 13^a—15^a, 13^b—15^b, and 13^c—15^c of relay R¹ connected in parallel. It will be apparent, therefore, that when all of the back contacts 13^a—15^a, 13^b—15^b, and 13^c—15^c are open, the bell L will be silent, but that, when any one of 4 these contacts is closed, the bell L will ring.

The operation of the apparatus shown in Fig. 1 as a whole is as follows: When a train moving from right to left enters section F—G, the train shunt will cause magnet A to become deenergized, 4 and back contact 13^a—15^a of relay R¹ will therefore become closed and will cause bell L to start to ring. When the train enters section E—F, magnet B will become deenergized and will cause the front contacts of relay R¹ controlled by this 5 magnet to open and the back contacts controlled by this magnet to become closed. The opening of front contact 11^b—14^b will interrupt the circuit for magnet A, and will thus cause magnet A to remain deenergized as long as magnet B remains 5 deenergized. The opening of front contact 10^b—14^b will interrupt the circuit for magnet C, and will thus cause magnet C to also become deenergized. The energization of this latter magnet will cause the front contacts of relay R¹ controlled thereby to open, but the back contacts controlled thereby will remain open due to the interlocking mechanism. The closing of back contact 13^b—15^b will close the circuit for bell L at this contact, but since the circuit for bell L is already 6 closed at back contact 13^a—15^a, the closing of back contact 13^b—15^b will have no effect of the remainder of the apparatus. As the train continues to traverse the stretch S, no further change 6 in the apparatus will take place until the rear end 70 of the train clears section E—F. When this happens, magnet B will become energized and will cause the back contacts controlled thereby to open and the front contacts controlled thereby to close. The closing of front contact 11^b—14^b will 75

restore the circuit for magnet A, while the closing of front contact 10^b—14^b will restore the circuit for magnet C. Magnet A will then pick up and open its back contacts and close its front contacts, but magnet C will remain deenergized due to the train shunt. When back contact 13^a—15^a opens, back contacts 13^b—15^b and 13^c—15^c will both be open, and as a result, the circuit for bell L will become interrupted, so that the bell will stop ringing. When the train departs from section D—E, magnet C will become energized and will cause the front contacts controlled thereby to become closed. All parts of the apparatus will then be restored to the positions in which they are shown in the drawings.

When a train traverses the stretch S from left to right, the operation of the apparatus is similar to that just described, and it is believed that this operation will be apparent from the foregoing description and from an inspection of the drawings without further detailed description.

It will be seen from the foregoing that a train approaching the crossing H in either direction will cause the bell L to start ringing as soon as the train enters either section D—E or F—G, and the bell will continue to ring until the train has completely passed section E—F.

It will be noted that as shown in the drawings the magnets A and C are slow releasing magnets. The reason for making these magnets slow releasing is to insure that the armatures controlled by these magnets will not drop quickly enough to cause the interlocking apparatus to fail to function when either of these magnets becomes deenergized due to the previous deenergization of magnet B. The relay will, however, usually function in the proper manner when the magnets A and C are of the ordinary acting type.

It should also be noted that since the deenergization of magnet B causes the circuits for both magnets A and C to become interrupted, back contact 13^a—15^a or back contact 13^c—15^c will always be closed when contact 13^b—15^b is closed, and as a result, the bell L will function in the manner described whether or not contact 13^b—15^b is included in the circuit for bell L, the only reason for including this contact in the circuit for bell L being to provide an additional degree of protection against improper operation of the apparatus.

One advantage of controlling a highway crossing signal in the manner described above is that the directional selection for cutting off the operation of the highway crossing signal is made at the crossing proper, thus eliminating circuit lockouts due to train movements in sections D—E and F—G. This is particularly desirable where a switch is located in either section D—E or section F—G, since the reversal of the switch while a train is in the other section, or the entry of a train into the other section while the switch is reversed, will not prevent a warning from being given at the crossing as long as the train has not proceeded past the crossing to the position in which it clears section E—F.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track divided into first, second, and third consecutive

track sections, a highway intersecting said second section, an interlocking relay comprising first, second, and third armatures controlled by first, second, and third electromagnets, respectively, said armatures being interlocked in such manner that movement of said second armature away from said second electromagnet restricts the subsequent movement of said first and third armatures away from said first and third electromagnets, a source of track circuit current connected with each of said track sections, means for connecting said second magnet with said second section, means for connecting said first and third magnets with said first and third sections when and only when said second magnet is energized, and a highway crossing signal located adjacent the intersection of said highway and said stretch and controlled by said interlocking relay.

2. In combination, a stretch of railway track divided into first, second, and third consecutive track sections, a highway intersecting said second section, an interlocking relay comprising first, second, and third armatures controlled by first, second, and third electromagnets, respectively, said armatures being interlocked in such manner that movement of said second armature away from said second electromagnet restricts the subsequent movement of said first and third armatures away from said first and third electromagnets, a source of track circuit current connected with each of said track sections, means for connecting said second magnet with said second section, means for connecting said first and third magnets with said first and third sections when and only when said second magnet is energized, a highway crossing signal located adjacent the intersection of said highway and said stretch, and a circuit for said signal including a back contact controlled by said first armature connected in multiple with a back contact controlled by said third armature.

3. In combination, a stretch of railway track divided into first, second, and third consecutive track sections, a highway intersecting said second section; an interlocking relay comprising first, second, and third armatures movable toward and away from first, second, and third electromagnets, respectively, and each provided with front contacts which are closed when and only when such armature is moved toward its associated electromagnet and with back contacts which are closed when and only when such armature is moved its full stroke away from its associated electromagnet, said first and third armatures being mechanically interconnected with said second armature in such manner that said first and third armatures are prevented from moving their full strokes away from the associated electromagnets if said second armature is first moved away from said second electromagnet, a track circuit for said first section including said first magnet and a front contact controlled by said second magnet, a track circuit for said second section including said second magnet, a track circuit for said third section including said third magnet and a front contact controlled by said second magnet, and a highway crossing signal located adjacent the intersection of said highway and said stretch controlled by back contacts of said magnets.

4. In combination, a stretch of railway track divided into first, second, and third consecutive track sections, a highway intersecting said second section; an interlocking relay comprising first, second, and third armatures movable toward and

away from first, second, and third electromagnets, respectively, and each provided with front contacts which are closed when such armature is moved toward its associated electromagnet and with back contacts which are closed when and only when such armature is moved its full stroke away from its associated electromagnet, said first and third armatures being mechanically interconnected with said second armature in such manner that said first and third armatures are prevented from moving their full strokes away from the associated electromagnets if said second armature is first moved away from said second electromagnet, a track circuit for said first section including said first magnet and a front contact controlled by said second magnet, a track circuit for said second section including said second magnet, a track circuit for said third section including said third magnet and a front contact controlled by said second magnet, a highway crossing signal located adjacent the intersection of said highway and said stretch, and an energizing circuit for said signal including a back contact controlled by said first armature connected in multiple with a back contact of said third armature and a back contact of said second armature.

5. In combination, a stretch of railway track divided into first, second, and third consecutive track sections, a highway intersecting said second section; an interlocking relay comprising first, second, and third armatures movable toward and away from first, second, and third electromagnets, respectively, and each provided with front contacts which are closed when such armature is moved toward its associated electromagnet and with back contacts which are closed when and only when such armature is moved its full stroke away from its associated electromagnet, said first and third armatures being mechanically interconnected with said second armature in such manner that said first and third armatures are prevented from moving their full strokes away from the associated electromagnets if said second armature is first moved away from said second electromagnet, a track circuit for said first section including said first magnet and a front contact controlled by said second magnet,

a track circuit for said second section including said second magnet, a track circuit for said third section including said third magnet and a front contact controlled by said second magnet, a highway crossing signal located adjacent the intersection of said highway and said stretch, and an energizing circuit for said signal including a back contact of said first armature connected in multiple with a back contact of said third armature and a back contact of said second armature.

6. In combination with a stretch of railway track which is crossed by a highway and divided into three consecutive sections the central of which includes the length of track which said crossing embraces; a protective signal associated with said crossing; an interlocking relay comprising three electromagnets, an armature which moves towards each of said magnets when the magnet is energized and away therefrom when the magnet is deenergized, interlocking means which prevent the first and third of said armatures from moving their full strokes away from the first and third of said magnets if the second armature is first moved away from the second magnet, a back contact operated by said first armature, a back contact operated by said third armature, and two front contacts operated by said second armature; means for supplying track circuit energy to the rails of each of said sections; a circuit through which the second magnet of said relay is at all times connected to the rails of said central track section; a circuit including one of said front contacts of the relay through which said first magnet of the relay is connected to the rails of one of said two remaining track sections only when said second winding is energized; a circuit including the other of said front contacts through which said third magnet of the relay is connected to the rails of the third track section also only when said second winding is energized; and a circuit including said two back contacts of the relay through which said crossing signal is supplied with operating energy whenever either of said first and third armatures of the relay is fully released.

WILLIAM H. CLAUS.
